Inventor

By J. W. Wiley

UNITED STATES PATENT OFFICE.

AUGUST KINDERMANN, OF CLEVELAND, OHIO.

WRENCH.

SPECIFICATION forming part of Letters Patent No. 338,078, dated March 16, 1886.

Application filed August 1, 1884. Serial No. 139,413. (No model.)

To all whom it may concern:

Be it known that I, AUGUST KINDERMANN, a citizen of the United States, and a resident of Cleveland, in the county of Cuyahoga and 5 State of Ohio, have invented certain new and useful Improvements in Wrenches, of which the following is a description.

The invention relates to that class of wrenches in which a sliding jaw is adjustable 10 toward or from a fixed jaw, and in which the relation of the several parts is such that the pressure upon the nut or other object which is gripped by the jaws is increased in exact proportion to the increase of the force exerted 15 upon the handle of the wrench.

The invention consists in certain improvements in the details of construction in a wrench of the character above described, whereby the strength of the same is increased, 20 whereby it is made readily and conveniently operable in difficult situations, and whereby it is readily convertible from a nut-wrench into a pipe-wrench.

In the drawings, Figure 1 is a side elevation 25 of the wrench. Fig. 2 is an elevation of the interior face of the sliding jaw. Fig. 3 is a side elevation of the sliding jaw. Fig. 4 is an irregular section on the broken line $x-x$ of Fig. 3. Fig. 5 is a view similar to that shown 30 in Fig. 4, showing a modified form of construction of portions of the device.

A is the fixed jaw, the rearwardly-projecting-shank A^2 of which is centrally slotted to receive the middle, recessed portion (best 35 seen in Fig. 2) of the sliding jaw B, and is provided with a perforation, a , to receive a pin, A' , by which the jaw is pivotally connected to the handle C, which has a corresponding perforation, c , through which also 40 the pivot-pin A' extends. Near the rear extremity of the shank of the fixed jaw it is provided with a curved or segmental slot or perforation, a' , to receive a pinch-screw, a'' , which is adapted to engage with a threaded 45 cavity, c' , in the face of the handle C. The projecting portion of the face of the jaw B, near the vertical center of the jaw, is provided with a dovetailed recess or groove, b , to receive a corresponding dovetailed slide, E, 50 which at its upper extremity terminates in a beveled portion, e , the lower extremity of which projects slightly outward from the main

body of the slide, and terminates in a tooth, e' , and which in its lower portion is provided with a pin, e'' , which extends transversely 55 through it, as seen in Fig. 2. The pin e'' , when the slide is in its most elevated position, is brought into contact with a shoulder or stop, d' , upon the face of the jaw.

In each of its lateral faces the jaw B has a 60 shallow fan-shaped recess, b'' , to receive respectively the right and left members, $D' D'$, of a link, D, which connects the jaw B and the handle C together, a slot, d , curved at either extremity, being formed in each of the 65 clasping parts or jaws D' to receive a pin, d' , which extends through the middle recessed portion of the jaw B from side to side thereof.

The jaws A and B are provided, respectively, with inclined faces F and F' on either side 70 thereof. The curved end portion of the handle C has a central slot or cavity, C', to receive the rear end of the link D, which at this as well as at the opposite end has a short slot, which at either extremity is curved to 75 suitably fit a second pivot-pin, d' . The inner or engaging face of the fixed jaw A is preferably provided with a recess, 2, as seen in Fig. 1, which extends across the same.

In Fig. 5 the link D is shown as of uniform 80 thickness from end to end, instead of being forked, as in Fig. 4, and the jaw B is shown as provided with a central slot, instead of the two lateral recesses b'' , as in that figure, and this construction may be adopted when the 85 wrench is made of small dimensions for light work. Ordinarily, however, the construction shown in Fig. 4 will be preferred, as insuring greater firmness and strength.

It will be observed that the perforation c 90 for the pivot-pin A' is formed in the solid portion of the handle at a considerable distance from the end of the handle and from the slot or cavity in the same—a construction which obviates all liability to fracture of the handle 95 by reason of strain upon the pivot-pin. The jaw B will be moved toward the fixed jaw by movement of the handle in the direction of the arrow shown in Fig. 1, while a reverse movement of the handle will withdraw it.

By reason of the provision of the slide E the device may be instantly adapted for use as a pipe-wrench, the projecting tooth e' being brought into contact with the body of the

pipe at a point opposite the recess 2 in the jaw A.

The provision of the inclined faces F and F' renders it practicable to apply this portion of the wrench in situations in which an ordinary wrench, or the upper ends of the jaws of this wrench, could not be brought to bear.

The provision of the pinch-screw permits adjustment of the jaws to nuts of any given size, and prevents the fall of the handle on its pivot when the wrench is applied where the nut is difficult of access—as, for instance, when the nut is directly over the head of the operator, or when it is near the floor.

15 Through the provision of the slots *d* in the link D a movement of the link upon its pins *d'* is permitted, so that when the handle is moved to close the jaws the force of the pressure exerted upon the link is brought to bear 20 directly upon the jaw and upon the handle, and the pins are wholly relieved.

I have described the wrench as provided with a curved slot, *a'*, in both members of the shank of the jaw A; but it is obvious that a 25 single slot and a single pinch-screw will be sufficient to effect the described adjustment of the parts.

It will be understood that the slide E is so fitted within the groove *b* as to be maintained 30 in adjustment by frictional contact alone.

Having described my invention, I claim—

1. The combination of the jaw A, having the curved slot *a'*, the pinch-screw *a''*, and the handle C, pivotally connected to the jaw A, 35 and carrying the sliding jaw B.

2. The combination, in a wrench, of a fixed recessed jaw, and a jaw which is slidable upon the shank of the fixed recessed jaw and which is provided on its engaging face with an adjustableslide, which carries an engaging-tooth, which, when the slide is adjusted inwardly, rests against the shank of the fixed jaw, and which, when the slide is in its outward adjustment, is opposite the recessed portion of 45 the fixed jaw.

3. A wrench one of the jaws of which is

provided with a groove, in which is a slide which carries a projecting tooth, the body of the slide being contained within the groove in the jaw, and the body of the tooth being 50 transverse to the face of the jaw and outside the body thereof, so that when the tooth is not in position for engagement the face of the jaw is left plain and unobstructed.

4. A wrench one of the jaws of which is 55 provided on its engaging face with an adjustable slide, E, for engagement with a pipe or other object which has a curved or rounded surface.

5. The combination, with the fixed jaw A, 60 of the sliding jaw B, grooved as described and carrying the adjustable slide E, substantially as set forth.

6. The combination, with the jaw A, having recess 2, of the jaw B, having groove *b* 65 and slide E.

7. The combination, with the jaw A, having recess 2, and inclined faces F, of the jaw B, having slide E and inclined faces F'.

8. The combination, with the jaw A, having recess 2, and pivotally connected to the handle C, of the jaw B, having slide E, and connected by link D to the handle C.

9. The combination of the jaw B, having recesses *b''' b'''*, the handle C, having cavity C', 75 and the link D, having the members D' D'.

10. The combination, with the jaw B and the handle C, of the link D, having the slots *d* at the ends thereof, whereby when the sliding jaw B is moved toward the fixed jaw the pins 80 *d'* are relieved from strain.

11. The combination, with the jaw B, having recesses *b'''*, of the link D having a slot in each end thereof, the pins *d'*, and the handle C, having central slot, C', and perforation *c*, 85 which extends through the unslotted portion of the handle.

AUGUST KINDERMANN.
